UNITED STATES PATENT OFFICE

121,264

DESIGN FOR A COMBINATION PULSE COUNT AND BLOOD PRESSURE INDICATING MA- CHINE

Bradlee W. Williams and Homer S. Williams,
Chicago, Ill., assignors to Tech Equipment
Company, Chicago, Ill., a corporation of Illinois

Application March 20, 1940, Serial No. 91,092

Term of patent 14 years

To all whom it may concern:

Be it known that we, Bradlee W. Williams and Homer S. Williams, citizens of the United States, residing at Chicago, in the county of Cook and State of Illinois, have invented a new, original, and ornamental Design for a Combination Pulse Count and Blood Pressure Indicating Machine, of which the following is a specification, reference being made to the accompanying drawing, forming a part thereof in which

Fig. 1 is a front elevational view of a combina-

tion pulse count and blood pressure indicating machine embodying our new design;

Fig. 2 is a side elevational view of the same;
and

Fig. 3 is a top plan view thereof.

We claim:

The ornamental design for a combination pulse count and blood pressure indicating machine, as shown.

BRADLEE W. WILLIAMS.
